UNITED STATES PATENT OFFICE

149,681

DESIGN FOR A DOUGHNUT SUGARING
MACHINE

Ernest J. Roth, Rockleigh, N. J., assignor to Joe
Lowe Corporation, New York, N. Y., a corpora-
tion of Delaware

Application July 17, 1946, Serial No. 131,646

Term of patent 14 years

(Cl. D55—1)

To all whom it may concern:

Be it known that I, Ernest J. Roth, a citizen of the United States, residing at Rockleigh, in the county of Bergen and State of New Jersey, have invented a new, original, and ornamental Design for a Doughnut Sugaring Machine, of which the following is a specification, reference being had to the accompanying drawings, forming part thereof, in which:

Figure 1 is a front elevational view of a doughnut sugaring machine, showing my new design;

Figure 2 is a perspective view of the doughnut sugaring machine shown in Figure 1, showing one end and the opposite side thereof; and

Figure 3 is an end elevational view of the doughnut sugaring machine shown in Figure 2,

showing the opposite end of the same.

What I claim is:

The ornamental design for a doughnut sugar-
ing machine, as shown.

ERNEST J. ROTH.
